Claims priority, application Germany Dec. 31, 1959

5 Claims. (Cl. 102—91)

The present invention relates to a composite projectile and more particularly to a special projectile for use in cartridges for the hunting of game of all types.

Depending upon the particular construction, known hunting shells or cartridges possess the property of totally or partially disintegrating or breaking up within the animal after the animal has been shot. In connection with the H-jacket shell type construction, for example, a groove is defined in the projectile body so as to form a cylindrical penetrating shot for effectively bringing down the hunted game. However, in certain cases, unfortunately, an open channel is not formed in the animal body nor does the projectile emerge from the wounded animal.

It is an object of the present invention to overcome the foregoing disadvantages and to provide a composite projectile specially adapted for hunting game having both a hard projectile mass and a soft projectile mass therewithin.

Other and further objects of the invention will become apparent from a study of the within specification and the accompanying drawing in which

The figure illustrates a cross-sectional view of a composite projectile in accordance with the present invention.

It has been found, in accordance with the present invention, that an effective composite projectile may be provided for hunting game, which comprises a hard projectile mass having a hard jacket therefor and a soft projectile mass having a separate jacket therefor. The hard jacket is provided with a softer forward extension portion at one end enclosing partially the soft projectile mass and its separate jacket, the remainder of the soft projectile mass extending past the end of said softer forward extension portion so as to form the composite projectile tip.

The composite projectile tip is preferably provided with an outwardly diverging conical recess, the apex angle of the conical portion of which may vary within fairly wide limits. Moreover, the end of the soft projectile mass enclosed partially within the softer forward extension portion remote from the projectile tip is desirably frusto-conically shaped. By providing the conical recess in the composite projectile tip, a controllable disintegration of the projectile may be attained depending upon the angle of the conical recess. It will be appreciated that as this angle changes the projectile disintegration will occur earlier or later as the same passes through the animal body.

By dint of the particular construction of the composite projectile, a form is achieved wherein such projectile or bullet is capable of compression, facilitating the passage of the same through the barrel of the hunting weapon employed, considering the dimensional tolerances of the bore passage of such hunting weapon. Advantageously, the construction in accordance with the present invention permits the desired disintegration of one projectile mass in the animal body, yet guarantees an exit opening due to the presence of a sufficiently strong piercing body. Thus, it is seen that the soft projectile mass having the conical recess therein will disintegrate as desired while the hard projectile mass will cause the channel to be formed through the animal body and will also guarantee an exit opening in the animal hide.

Referring to the drawing, the figure illustrates a composite projectile for use in shells, bullets, cartridges, and the like, especially for hunting purposes, having a hard lead projectile mass or plug 3 enclosed within a hard steel elongated jacket 1, said jacket being provided with a softer steel forward extension approximately along the distance 2. The softer forward extension portion is achieved by inductive heat treatment, such as by heat tempering the forward portion of jacket 1. As a result, a soft, elastic, flexible zone is attained, having the advantageous properties desired in accordance with the instant construction. A soft lead projectile mass or elongated plug 5 is enclosed within a soft copper jacket 4. The rearward end of such plug 5 is disposed in abutting engagement with the correspondingly situated portion of the hard plug 3, said plug 5 being partially enclosed within the softer forward extension 2 of jacket 1. The remainder of the soft lead plug 5, extending past the forward end of extension portion 2, is inwardly directed so as to form the tip of the composite projectile. Such tip portion is provided with an outwardly diverging conical recess 6 having the angle α . It will be appreciated that, in accordance with the present invention, this angle may be adjusted within wide limits, for instance, so as to form a conical recess 6' having an angle α' depending upon the timing and extent to which the soft lead plug 5 is to be disintegrated within the animal body. Of course, the hard plug 3 will be sufficient to guarantee a piercing of the animal hide and a channeling through the animal body.

The hard lead plug 3 may be formed of any lead alloy contributing the desired characteristics required for channeling and piercing the animal while the soft lead plug 5 may carry a soft copper jacket having particularly high expansion characteristics. Advantageously, the rearward portion of soft lead plug 5 is slightly frusto-conically shaped in order to minimize transverse reinforcement which might otherwise decrease the desired disintegration or breaking-up of this particular mass of the composite projectile.

Naturally, the particular type of game to be shot, the projectile velocity, the projectile weight, the disintegration propensity of the projectile and therewith the effect in the animal's body are specifically influenced, in accordance with applicant's construction, by the presence of the conical recess in the composite projectile tip as well as the outwardly diverging angle of such recess. If desired, the rearmost portion of the composite projectile—i.e., the rearmost portion of hard lead plug 3—may be similarly frusto-conically shaped in the manner of the preferred shaping of the rearmost portion of soft lead plug 5.

We claim:

1. Composite projectile comprising a rearward hard projectile mass having a hard jacket therefor and a separate forward soft projectile mass having a separate soft jacket therefor, said hard jacket having a soft forward extension portion at one end, enclosing partially the rearward portion of said soft projectile mass and its separate jacket, the remainder of said soft projectile mass and its separate jacket extending past the end of said soft forward extension portion to form the composite projectile tip.

2. Projectile according to claim 1 wherein said composite projectile tip is integral and provided with an outwardly diverging conical recess.

3. Projectile according to claim 2 wherein the end of said soft projectile mass enclosed partially within said soft forward extension portion remote from said tip is invertedly frusto-conically shaped.

4. Composite projectile comprising a softer forward

projectile mass and a harder rearward projectile mass, said forward projectile being enclosed within a softer jacket and said rearward projectile being enclosed within a harder jacket, said projectiles being discrete with respect to one another, said harder jacket having a softer forward extension portion at one end thereof, enclosing partially the rearward portion of said forward projectile and the rearward portion of said softer jacket, the forward portion of said rearward projectile being disposed within said forward extension portion in abutment with the rearward portion of said softer jacket, the forward portion of said forward projectile forming the composite projectile tip.

5. Composite projectile for hunting game comprising an elongated hard steel outer jacket portion containing a hard lead projectile mass therewithin, an elongated, copper jacket enclosed soft lead projectile means having a rear portion and a front portion, said projectiles being discrete with respect to one another, said hard steel outer jacket portion having a forward extension portion of heat-treated steel which is softer than the remaining hard steel outer jacket portion, said forward extension portion partially enclosing said elongated, copper jacket enclosed

soft lead projectile mass with the rear portion of said copper jacket enclosed lead projectile mass abutting said hard lead projectile mass, the remainder of said elongated, copper jacket enclosed soft lead projectile mass extending past the end of said forward extension portion, the front portion of said enclosed soft lead projectile mass forming the tip of the composite projectile mass, said tip being integral and provided with an outwardly diverging conical recess.
